ALFRED S. MAPPETT, OF PHILADELPHIA, PENNSYLVANIA, ASSIGNOR TO FOWLER & WOLFE MANUFACTURING COMPANY, OF PHILADELPHIA, PENNSYLVANIA, A CORPORATION OF PENNSYLVANIA.

ADJUSTABLE SUPPORT FOR WALL-RADIATORS.

1,236,855.

Specification of Letters Patent. Patented Aug. 14, 1917.

Application filed October 25, 1916. Serial No. 127,535.

To all whom it may concern:

Be it known that I, ALFRED S. MAPPETT, a citizen of the United States, residing at Philadelphia, in the county of Philadelphia and State of Pennsylvania, have invented a certain new and useful Improved Adjustable Support for Wall-Radiators, of which the following is a specification.

The present invention relates to an adjustable support for radiator sections of the wall type and has for an object to provide a means to support an end of a radiator whereby expansion and contraction take place freely without placing strain or stress upon the radiator or its associated parts.

In wall radiators composed of a plurality of superposed sections arranged in the same plane, it has been found where the upper sections are supported at each end by a fixed nipple threaded into each section that the relative variation in the length of the radiator sections causes the nipples to crack, break or be otherwise so distorted as to cause leakage and damage. By my present invention, I have overcome the foregoing defects through the elimination of a fixed nipple support at one end and the provision of a removable adjustable member which may be inserted at any convenient point between the sections and adjusted to supporting conditions without placing any limitation upon the free expansion or contraction of the radiator.

A further object of the invention is to provide an adjustable support having suitable guide surfaces upon which the part supported by such surface or surfaces is free to move relatively thereto as conditions require.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings:

Figure 1 represents a side elevation of a

wall radiator showing the adjustable support of my invention in operative position. 55

Fig. 2 represents a section on line 2—2 of Fig. 3.

Fig. 3 represents a plan of the support.

Fig. 4 represents a section in elevation of one of the saddle members. 60

Fig. 5 represents an elevation of the connecting nipple.

1 designates generally a separator and support for radiator sections of the type more particularly known as wall radiators 65 wherein a plurality of radiator sections are connected together and supported adjacent to and in substantially parallel relation to a wall. In radiators of this type, it has been found, where one section is superposed upon another as illustrated in Fig. 1, that with supporting nipples at each end, there is practically no allowance for the expansion and contraction of the radiator due to variations in temperature of the surrounding atmosphere or the medium within the section. As a result therefore of this natural tendency of the metal to vary under temperature changes it has been found that the nipples break or crack causing leakage 80 and its attendant trouble. By my present invention, the construction of such radiators is not only materially simplified but any section is free to expand or contract without placing the connectors or supports under stress or strain. 85

The adjustable support 1 consists, as illustrated by way of example, of three parts,—an upper tubular saddle 2, a lower tubular saddle 3 and an intermediate control nipple 90 4, which in assembled condition are adapted to be positioned between an upper and a lower wall radiator section and support the former in such a manner as to permit free relative movement between the two sections. 95 The upper saddle 2 is preferably provided with a screw threaded portion 5 adapted to receive the threaded end 6 of the nipple 4 and the lower saddle 3 is also provided with a threaded portion 7 to receive the opposite 100 threaded end 8 of the same nipple. It should be noted that the ends of the nipple 4 are oppositely threaded, that is one is a right hand thread and the other a left hand thread so that as the nipple 4 is turned in 105 one direction or the other, the saddles will

be simultaneously moved either toward or away from each other. Except for this difference in the threading of the two saddles, their construction is similar and hence the 5 detailed description will be limited to one though the same reference numerals will be used with both to indicate like parts. The saddles, as will be understood, are preferably of tubular construction and at the 10 free end are transversely cut to provide a supporting surface 9 and a pair of aligned seats 10, the former having the general contour of the coöperating radiator face and the latter being adapted to receive the rib 15 11 of the radiator section. The surfaces 9 in addition to forming a support have the function of a guide or way upon which the radiator element may move while expanding or contracting. The seats 10 prevent lateral 20 displacement of the adjustable support and therefore insure the parts being retained at all times in operative position.

The control nipple 4, in the preferred form, is provided with an opening or openings 25 12 for the insertion of a suitable implement, such as a spanner wrench or the like, whereby it may be properly turned to cause the required movement of the two saddles. Thus in placing the device for use, 30 the saddles are normally sufficiently close together to permit the free insertion of the support between the radiator sections, the lower saddle seating upon the upper face of the lower radiator section while the seats 35 10 receive the rib 11. The nipple 4 is now rotated to cause separation of the two saddles and consequently the upper saddle rises beneath and into contact with the lower face of the upper radiator section while the seats 40 9 straddle the ribs 11 as an additional guard against the displacement of the device. It is preferable to tighten the adjustable members between the radiator sections just enough to maintain the upper section correctly supported without shearing stress 45 upon any of the fixed nipples, though the degree of tightness may vary quite widely without materially increasing the friction sufficiently to prevent the relative sliding 50 movement due to expansion or contraction.

The device in effect is loosely positioned between the radiator sections and in using the word "loosely" in the claims it is to be understood that it is employed with the 55 meaning that the device is not fixed to either section other than by frictional contact.

It will now be apparent that I have devised a novel and useful construction which embodies the features of advantage enumerated 60 as desirable in the statement of the invention and the above description and while I have in the present instance shown

and described the preferred embodiment thereof which has been found in practice to give satisfactory and reliable results it is to 65 be understood that the same is susceptible of modification in various particulars without departing from the spirit or scope of the invention or sacrificing any of its advantages. 70

What I claim is:

1. In a device of the character stated, the combination of a radiator section fixedly supported at one end and an adjustable support loosely seating beneath the opposite 75 end, said support having a guide surface whereby said radiator section is free to move under expansion or contraction.

2. In a device of the character stated, the combination of a radiator composed of superposed sections, the upper section of a pair of sections being connected at one end to the lower section by a threaded nipple connection and an adjustable support adapted to be loosely inserted between said sections at 80 the free end whereby said upper section is supported for free expansion and contraction. 85

3. In a device of the character stated, the combination of a radiator composed of superposed sections the upper section of a pair of sections being connected at one end to the lower section by a nipple connection and an adjustable support provided with upper and lower guide surfaces adapted to respectively 90 seat loosely upon the lower face of the upper radiator section and the upper face of the lower section whereby free expansion and contraction can take place between said sections. 95

4. In a device of the character stated, the combination of a radiator composed of superposed sections, the upper section of a pair of sections being connected at one end to the lower section by a nipple, an adjustable support provided with upper and lower guide surfaces adapted to respectively seat loosely upon the opposed faces of said radiator sections and means to prevent lateral displacement of said adjustable support. 100 105

5. In a device of the character stated the combination of a radiator composed of superposed sections, the upper section of a pair of sections being fixedly connected at one end to the lower section and an expandible support adapted to be loosely inserted between said sections at the free end whereby unrestricted longitudinal expansion and contraction can take place between said sections. 115 120

In testimony whereof, I have hereunto signed my name.

ALFRED S. MAPPETT.
